VICTOR SCHLEYER, OF ANDERSON, INDIANA, ASSIGNOR TO MIDWEST ENGINE CORPORATION, OF INDIANAPOLIS, INDIANA, A CORPORATION OF DELAWARE.

DEEP-WELL-PUMP LUBRICATION.

Application filed February 16, 1923. Serial No. 619,347.

To all whom it may concern:

Be it known that I, VICTOR SCHLEYER, a citizen of the United States, residing at Anderson, in the county of Madison and 5 State of Indiana, have invented a new and useful Deep-Well-Pump Lubrication, of which the following is a specification.

It is the object of my invention to provide an effective lubricating system for 10 deep-well pumps; and to minimize the loss of lubricant, especially when oil is used as a lubricant, and to make it possible to change the lubricant simply and readily whenever desired; and to provide a balanced-pressure system in which the pressure developed by the main pump is used to build up a balancing pressure in the lubricating system, and to do this while permitting the lubricating system to be a circulating system which when the pump is 20 operated may use a lubricant other than water without material contamination from the water being pumped by the main pump.

The accompanying drawing illustrates my 25 invention:

Fig. 1 is a vertical central section through a deep-well pump embodying my invention; Fig. 2 is an enlargement of part of the lower portion of Fig. 1, with the lubricant-pump, to show some details; and Fig. 3 is 30 a detail enlargement of the check-valve of Figs. 1 and 2, which check-valve admits water from the well to produce the balancing pressure in the lubricating system.

The main pump 9, shown as a single-stage pump though that is not essential, has its rotor 10 mounted on the lower end of a vertical shaft 11 suitably driven from the top, and the rotation of the rotor 10 5 draws water into the inlet 12 of the pump casing and discharges it vertically upward through a suitable discharge pipe 13. The stationary part 14 of the pump 9 may have the usual vanes 15 for preventing the whirling 10 of the water, and the usual main bearing 16 above the rotor 10. Further, the vertical shaft 11 is surrounded by a pipe 17, within which may be suitable intermediate 15 and top bearings 18 and 19. The parts so far described may be of any desired construction, and in themselves are not new.

Just above the main pump 9 I provide a lubricant-pump 20, which has a small rotor

21 on the shaft 11. Just above the rotor 21 I provide a bearing 22 for the shaft 11, 55 while below such rotor 21 and between it and the main bearing 16 I preferably provide a carefully packed bearing 23 for the shaft 11. The lubricant-pump 20 receives its supply from above, through the pipe 17 60 and past the bearing 22, and the rotor 21 discharges outwardly into a space 24 in the lubricant-pump 20, which space 24 is connected to a discharge pipe 25 which leads upward, usually outside of the casing 13. 65

At the top of the casing 13, and preferably directly over it, is a closed reservoir 30, having a valved drain-pipe 31 near the bottom and a valved overflow-pipe 32 near the top. The upper end of the casing 17 is 70 supplied with liquid through a pipe 33, which may receive its supply either from a source of water under pressure, such as a city main, when a valve 34 is open, or from the reservoir 30 through a filter 35 and outlet pipe 36 which communicates with the reservoir 30 near the top thereof, the pipe 36 having a valve 37; so that by the manipulation of the valves 34 and 37 either water from the city main or liquid from the reservoir 30 may be supplied to the pipe 17. 80

An open supply-tank 38, preferably higher than the closed reservoir 30, gives a supply of the lubricant, usually oil, which is to be used for lubricating the deep-well 85 pump while it is in operation. A small pilot pump 39 is driven from the shaft 11, by a belt 40 and suitable pulleys, being shown as having its inlet 41 on the bottom and its outlet 42 on the top. The inlet 41 may 90 be connected to the lower part of the supply-tank 38, by opening a valve 43, and the outlet 42 connected to the closed reservoir 30 through a control valve 44 and a check-valve 45; so that when the valves 43 and 44 are open, the pilot pump 39 pumps liquid from the supply-tank 38, and discharges it 95 into the closed reservoir 30. The inlet 41 may also be connected through a valve 46 to the upper end of the discharge pipe 25 100 from the lubricant-pump 20; and the discharge 42 of the pilot pump may be connected through a valve 47 to discharge through a filling pipe 48 into the supply tank 38.

Below the valve 46, the pipe 25 has two

side branches, one through a spill-cock 49, to discharge liquid when desired, and the other through a valve 50 and check-valve 51 to the closed reservoir 30. Below the 5 valves 49 and 50 and the branch pipes leading thereto, the pipe 25 may if desired have a valve 52; but this is rarely closed, and may be omitted. The closed reservoir 30 is suitably connected to a pressure gage 10 53, which indicates the accumulated pressure in said reservoir. By opening the valves 46 and 47, and closing the valves 43, 44, 49, and 50, the liquid forced upward through the pipe 25 may be sent on by the 15 pilot pump 39 into the supply-tank 38.

When first starting the deep-well pump, the valves 34, 52, and 50 are opened, and water from the city main is allowed to flow into the pipe 17, to fill it and the pipe 25, 20 and, if desired, the closed reservoir 30. The valve 32 is usually open at this time until it overflows to indicate that the system is full, though if desired the overflow may be either by the valved drain-pipe 31 or the 25 spill-cock 49. With the system full, the deep-well pump is started into operation. The lubricant-pump 20 circulates the liquid in the lubricating system.

The valve 34 is now closed, to shut off 30 the supply from the city main, and the valves 37, 43, and 44 are opened; at the same time, the spill-cock 49 is opened. As now the deep-well pump operates, the pilot pump 39 forces the operating lubricant, such as 35 oil, from the supply-tank 38 and past the check valve 45 into the closed reservoir 30, whence it flows through the filter 35 and valve 37 into the filler pipe 33 and thence into the pipe 17 in which the vertical shaft 40 11 is located. This lubricant forces the water ahead of it, and out through the spill-cock 49.

There is a fairly sharp line of demarcation between the water thus displaced and 45 the oil which displaces it, and as soon as the spill-cock 49 begins to discharge oil, as the fluid in the system is being moved with the combined action of the pumps 39 and 20, the spill-cock 49 is closed, and the valve 50 50 is opened if it was closed, so that the pipe 25 will discharge the oil into the closed reservoir 30. One or both of the valves 43 and 44 may now be closed, and, if desired, the pilot pump 39 may be thrown out of action.

The lubricant system is now filled with 55 the operating lubricant, obtained from the supply-tank 38, and circulates it from the reservoir 30 to the upper end of the pipe 17, down through such pipe to lubricate the 60 various bearings 19, 18, and 22, thence through the lubricant-pump 20, which produces the circulating force, and thence up by the pipe 25 and through the valves 52 and 50 back into the closed reservoir 30.

When the deep-well pump is to be shut

down, just before the shut-down, the liquid-displacement process is reversed, and the oil in the lubricant system is replaced by water. This is because the loss in lubricant occurs mainly while the pump is at rest, for during such times the oil if left in the lubricant system will force its way by gravity past the bearings into the water in the discharge pipe 13; so that when an oil-lubricated pump is started after a shut-down it has frequently been found that the pump is empty of lubricant. 70

To prevent this loss, and save the lubricant, I open the valves 34, 46, and 47, and close the valves 37, 43, 44, and preferably 80 50, and start the pilot pump 39 if it had been stopped, shortly before shutting down the deep-well pump. The water from the city main now forces the oil out of the pipe 17, the lubricant-pump 20, and the pipe 25, 85 and the pilot pump 39 takes the oil from the pipe 25 and lifts it back into the supply-tank 38. The operating lubricant is thus saved for use when the pump is again started. While the pump is shut down, the valves 34, 90 37, 52, and 42 are preferably all closed, to help hold the liquid in the lubricant system while the pump is at rest.

The lubricant system is thus a circulating system, with a downward flow through the 95 pipe 17 and an upward flow through the pipe 25. These are in hydrostatic balance. In addition to their balance between themselves, I also prefer to balance them against the pressure developed by the main pump 9 100 at the outlet thereof, to prevent both material in-leakage of water to contaminate the lubricant and material out-leakage of liquid from the lubricating system.

To this end, I connect the space 60 just 105 below the periphery of the rotor 21 through an in-flow check-valve 61 to a pipe 62 which has a filter head 63 in the main water column. The check-valve 61 permits water from the main water-stream to flow in 110 through the pipe 62 into the space 60. It is a standard check-valve construction, having a stationary outer shell 64 and a movable inner shell 65 with suitable ports which permit flow of water upward through the 115 valve into the space 60 when the inner shell is lifted off its seat, but prevents outflow of water when the inner shell is seated in the bottom of the outer shell 64.

Thus as the main pump 9 develops pressure, water is forced by such pressure into the pipe 62 and past the check-valve 61 into the space 60, building up pressure in such space until a balance is obtained between such pressure and the water-pressure in the 125 outside water-column. This pressure is built up because the lubricant system is a closed system; for the reservoir 30 is closed, and when the system is in operation there is no outlet to atmosphere save during the dis- 130

placing periods at the beginning and end of a run.

- Because of this balance, which is quickly attained, there is very little in-leakage of water to the lubricating system, and what water does leak in collects in the lower part of the closed reservoir 30, while the oil rises to the top of such closed reservoir and is drawn off through the filter 35 and pipe 36.
- 10 Further, by making the parts fairly accurate, there is very little out-leakage of lubricant, for there can be no out-flow past the check-valve 61, and the space 60 contains mainly water. Therefore, what out-leakage 15 there is past the packed bearing 23 is mainly water, and is replaced by incoming water through the check-valve 61 to maintain the balance of pressures. Even this out-leakage is minimized by the packing of such bearing 20 23; and by the close-fitting annular rings and grooves (shown clearly in Fig. 2) between the lower face of the rotor 21 and the upper face of the bearing 23.

By this balanced system of lubrication, I 25 find that I can operate the pump with a comparatively small quantity of oil, because loss of the oil is prevented both during the operation of the pump and while the pump is at rest.

30 I claim as my invention:

1. In a deep-well pump, the combination of a shaft extending down into the well, a rotary pump in the well, a water-discharge pipe extending up from said main pump, a lubricant-pump also located in the well close above said main pump, both of said pumps having rotors driven from said shaft, a lubricant-supply pipe leading to the intake of said lubricant-pump, a lubricant-discharge pipe extending upward from the outlet of said lubricant-pump, and a closed reservoir to which the upper ends of both said lubricant-supply pipe and said lubricant-discharge pipe are connected, said lubricant-pump having a check-valved connection to the interior of said water-discharge pipe permitting in-flow from said water discharge pipe to said lubricant-pump.

2. In a deep-well pump, the combination of a shaft extending down into the well, a rotary pump in the well, a water-discharge pipe extending up from said main pump, a lubricant-pump also located in the well, both of said pumps having rotors driven from said shaft, a lubricant-supply pipe leading to the intake of said lubricant-pump, a lubricant-discharge pipe extending upward from the outlet of said lubricant-pump, and a closed reservoir to which the upper ends of both said lubricant-supply pipe and said lubricant-discharge pipe are connected, said lubricant-pump having a check-valved connection to the interior of said water-discharge pipe permitting in-flow from said water discharge pipe to said lubricant-pump.

3. In a deep-well pump, the combination of a shaft extending down into the well, a rotary pump in the well, a water-discharge pipe extending up from said main pump, a lubricant-pump also located in the well, both of said pumps having rotors driven from said shaft, a lubricant-supply pipe leading to the intake of said lubricant-pump, a lubricant-discharge pipe extending upward from the outlet of said lubricant-pump, the upper ends of said lubricant-supply pipe and said lubricant-discharge pipe being interconnected to form a closed system, said lubricant-pump having a check-valve connection below its runner to the interior of said water-discharge pipe permitting in-flow from said water discharge pipe to said lubricant-pump.

4. In a deep-well pump, the combination of a shaft extending down into the well, a rotary pump in the well, a water-discharge pipe extending up from said main pump, a lubricant-pump also located in the well, both of said pumps having rotors driven from said shaft, a lubricant-supply pipe surrounding said shaft and leading to the intake of said lubricant-pump, a lubricant-discharge pipe extending upward from the outlet of said lubricant-pump, and a closed reservoir to which the upper ends of both said lubricant-supply pipe and said lubricant-discharge pipe are connected, said lubricant-pump having a check-valved connection to the interior of said water-discharge pipe permitting in-flow from said water discharge pipe to said lubricant-pump.

5. In a deep-well pump, the combination of a shaft extending down into the well, a rotary pump in the well, a water-discharge pipe extending up from said main pump, a lubricant-pump also located in the well, both of said pumps having rotors driven from said shaft, a lubricant-supply pipe leading to the intake of said lubricant-pump, a lubricant-discharge pipe extending upward from the outlet of said lubricant-pump, the upper ends of said lubricant-supply pipe and said lubricant-discharge pipe being interconnected to form a closed system, said lubricant-pump having a check-valved connection to the interior of said water-discharge pipe permitting in-flow from said water discharge pipe to said lubricant-pump.

6. In a deep-well pump, the combination of a shaft extending down into the well, a rotary pump in the well, a water-discharge pipe extending up from said main pump, a lubricant-pump also located in the well, both of said pumps having rotors driven from said shaft, a lubricant-supply pipe leading to the intake of said lubricant-pump, a lubricant-discharge pipe extending upward from the outlet of said lubricant-pump, and a closed reservoir to which the upper ends of both said lubricant-supply

pipe and said lubricant-discharge pipe are connected, the lubricant system formed by said lubricant-pump and its supply and discharge pipes having a check-valved connection near the bottom to the interior of said water-discharge pipe permitting water inflow from said water-discharge pipe to said lubricant system.

7. In a deep-well pump, the combination 10 of a shaft extending down into the well, a rotary pump in the well, a water-discharge pipe extending up from said main pump, a lubricant-pump also located in the well, both of said pumps having rotors driven from 15 said shaft, a lubricant-supply pipe leading to the intake of said lubricant-pump, a lubricant-discharge pipe extending upward from the outlet of said lubricant-pump, the upper ends of said lubricant-supply pipe 20 and said lubricant-discharge pipe being interconnected to form a closed system, the lubricant system formed by said lubricant-pump and its supply and discharge pipes having a check-valved connection near the 25 bottom to the interior of said water-discharge pipe permitting water inflow from said water-discharge pipe to said lubricant system.

8. In a deep-well pump, the combination 30 of a shaft extending downward into the well, a rotary pump in the well, a water-discharge pipe extending up from said main pump, a lubricant-pump also located in the well, both of said pumps having rotors 35 driven from said shaft, a lubricant-supply pipe leading to the intake of said lubricant-pump, a lubricant-discharge pipe extending upward from the outlet of said lubricant-pump, and a closed reservoir to which the 40 upper ends of both said lubricant-supply pipe and said lubricant-discharge pipe are connected, the lubricant system formed by said lubricant-pump and its supply and discharge pipes having a check-valved connection 45 near the bottom to the interior of said water discharge pipe permitting water inflow from said water-discharge pipe to said lubricant system, the connection of said lubricant-supply pipe to said closed reservoir being spaced upward from the bottom 50 of said reservoir.

9. In a deep-well pump, the combination 55 of a shaft extending down into the well, a rotary pump in the well, a water-discharge pipe extending up from said main pump, a lubricant-pump also located in the well, both of said pumps having rotors driven from said shaft, a lubricant-supply pipe leading to the intake of said lubricant- 60 pump, a lubricant-discharge pipe extending upward from the outlet of said lubricant-pump, the upper ends of said lubricant-supply pipe and said lubricant-discharge pipe being interconnected to form a closed 65 system, the lubricant system formed by said

lubricant-pump and its supply and discharge pipes having a check-valved connection near the bottom to the interior of said water-discharge pipe permitting water inflow from said water-discharge pipe to said 70 lubricant system, a lubricant-supply tank, water-supplying means, and valves for supplying lubricant from said tank or said water-supplying means to said lubricant system at will so that either water or said 75 lubricant may displace the other.

10. In a deep-well pump, the combination 80 of a shaft extending down into the well, a rotary pump in the well, a water discharge pipe extending up from said main pump, a lubricant-pump also located in the well, both of said pumps having rotors driven from said shaft, a lubricant-supply pipe leading to the intake of said lubricant-pump, a lubricant-discharge pipe extending 85 upward from the outlet of said lubricant-pump, the upper ends of said lubricant-supply pipe and said lubricant-discharge pipe being interconnected to form a closed system, the lubricant system formed by said 90 lubricant-pump and its supply and discharge pipes having a check-valved connection near the bottom to the interior of said water-discharge pipe permitting water inflow from said water-discharge pipe to said 95 lubricant system, a lubricant-supply tank, water-supplying means, and valves for supplying lubricant from said tank or said water-supplying means to said lubricant system at will so that either water or said 100 lubricant may displace the other, said connections and valves including a line for discharging displaced lubricant back to said lubricant-supply tank.

11. In a deep-well pump, the combination 105 of a shaft extending down into the well, a rotary pump in the well, a water-discharge pipe extending up from said main pump, a lubricant-pump also located in the well, both of said pumps having rotors 110 driven from said shaft, a lubricant-supply pipe leading to the intake of said lubricant-pump, a lubricant-discharge pipe extending upward from the outlet of said lubricant-pump, the upper ends of said lubricant-supply pipe and said lubricant-discharge 115 pipe being interconnected to form a closed system, said lubricant-pump having a check-valved connection to the interior of said water-discharge pipe permitting inflow from said water discharge pipe to said lubricant-pump, a lubricant-supply tank, water-supplying means, and valves for supplying lubricant from said tank or said water-supplying means to said lubricant 120 system at will so that either water or said lubricant may displace the other.

12. In a deep-well pump, the combination 125 of a shaft extending down into the well, a rotary pump in the well, a water-discharge 130

5 pipe extending up from said main pump, a
6 lubricant-pump also located in the well, both
7 of said pumps having rotors driven from
8 said shaft, a lubricant-supply pipe leading
9 to the intake of said lubricant pump, a
10 lubricant-discharge pipe extending upward
11 from the outlet of said lubricant-pump, the
12 upper ends of said lubricant-supply pipe
13 and said lubricant-discharge pipe being in-
14 terconnected to form a closed system, said
15 lubricant-pump having a check-valved con-
16 nection to the interior of said water-dis-
17 charge pipe permitting in-flow from said
18 water discharge pipe to said lubricant-
19 pump, a lubricant-supply tank, water sup-
20 plying means, and valves for supplying
21 lubricant from said tank or said water-sup-
22 plying means to said lubricant system at
23 will so that either water or said lubricant
24 may displace the other, said connections and
25 valves including a line for discharging dis-
26 placed lubricant back to said lubricant-
27 supply tank.

28 13. In a deep-well pump, the combination
29 of a shaft extending down into the well,
30 a rotary pump in the well, a water-dis-
31 charge pipe extending up from said main
32 pump, a lubricant-pump also located in the
33 well, both of said pumps having rotors
34 driven from said shaft, a lubricant-supply
35 pipe leading to the intake of said lubricant-
36 pump, a lubricant-discharge pipe extend-
37 ing upward from the outlet of said lubri-
38 cant-pump, the upper ends of said lubri-
39 cant-supply pipe and said lubricant-dis-
40 charge pipe being interconnected to form
41 a closed system, the lubricant system formed
42 by said lubricant-pump and its supply and
43 discharge pipes having a check-valved con-
44 nection near the bottom to the interior of
45 said water-discharge pipe permitting water
46 inflow from said water-discharge pipe to
47 said lubricant system, a lubricant-supply
48 tank, water-supplying means, valves for
49 supplying lubricant from said tank or said
50 water-supplying means to said lubricant
51 system at will so that either water or said
52 lubricant may displace the other, and a
53 pump driven from said shaft for forcing
54 lubricant to and from said supply tank.

55 14. In a deep-well pump, the combination
56 of a shaft extending down into the well,
57 a rotary pump in the well, a water-dis-
58 charge pipe extending up from said main
59 pump, a lubricant-pump also located in the
60 well, both of said pumps having rotors
61 driven from said shaft, a lubricant-supply
62 pipe leading to the intake of said lubri-
63 cant-pump, a lubricant-discharge pipe ex-
64 tends upward from the outlet of said
65 lubricant-pump, the upper ends of said
66 lubricant-supply pipe and said lubricant-
67 discharge pipe being interconnected to
68 form a closed system, the lubricant system
69 formed by said lubricant-pump and its sup-
70 plying and discharge pipes having a check-
71 valved connection near the bottom to the in-
72 terior of said water-discharge pipe permit-
73 ting water inflow from said water-dis-
74 charge pipe to said lubricant system, a
75 lubricant-supply tank, water-supplying
76 means, and valves for supplying lubricant
77 from said tank or said water-supplying
78 means to said lubricant system at will so
79 that either water or said lubricant may dis-
80 place the other, said connections and valves
81 including a line for discharging displaced
82 lubricant back to said lubricant-supply
83 tank, and a pump driven from said shaft
84 for forcing lubricant to and from said sup-
85 plying tank.

86 15. In a deep-well pump, the combination
87 of a shaft extending down into the well, a
88 rotary pump in the well, a water-discharge
89 pipe extending up from said main pump,
90 a lubricant-pump also located in the well,
91 both of said pumps having rotors driven
92 from said shaft, a lubricant-supply pipe
93 leading to the intake of said lubricant-
94 pump, a lubricant-discharge pipe extend-
95 ing upward from the outlet of said lubri-
96 cant-pump, a lubricant-supply tank, water-
97 supplying means, and valves and connec-
98 tions for supplying either lubricant from
99 said tank or water from said water-sup-
100 plying means to the lubricating system com-
101 posed of said lubricant-pump and its sup-
102 plying and discharge pipes, to displace either
103 water or lubricant by the other as de-
104 sired.

105 16. In a deep-well pump, the combination
106 of a shaft extending down into the well, a
107 rotary pump in the well, a water-discharge
108 pipe extending up from said main pump,
109 a lubricant-pump also located in the well,
110 both of said pumps having rotors driven
111 from said shaft, a lubricant-supply pipe
112 leading to the intake of said lubricant-
113 pump, a lubricant-discharge pipe extend-
114 ing upward from the outlet of said lubri-
115 cant-pump, a lubricant-supply tank, water-
116 supplying means, and valves and connec-
117 tions for supplying either lubricant from said
118 tank or water from said water-supplying
119 means to the lubricating system composed
120 of said lubricant-pump and its supply and
121 discharge pipes to displace either water or
122 lubricant by the other as desired, said valves
123 and connections including a lubricant-re-
124 turn pipe discharging into said supply tank
125 for supplying the lubricant thereto when
126 the lubricant in the lubricant system is dis-
127 placed by water.

128 17. In a deep-well pump, the combination
129 of a shaft extending down into the well, a
130 rotary pump in the well, a water-discharge
131 pipe extending up from said main pump, a
132 lubricant-pump also located in the well, both
133 of said pumps having rotors driven from
134 said shaft, a lubricant-supply pipe leading

- to the intake of said lubricant-pump, a lubricant-discharge pipe extending upward from the outlet of said lubricant-pump, a lubricant-supply tank, water-supplying means, and valves and connections for supplying either lubricant from said tank or water from said water-supplying means to the lubricating system composed of said lubricant-pump and its supply and discharge pipes to displace either water or lubricant by the other as desired, and a pump driven from said shaft for feeding lubricant from said supply-tank to said lubricant system. 10
18. In a deep-well pump, the combination of a shaft extending down into the well, a rotary pump in the well, a water-discharge pipe extending up from said main pump, a lubricant-pump also located in the well, both of said pumps having rotors driven from said shaft, a lubricant-supply pipe leading to the intake of said lubricant-pump, a lubricant-discharge pipe extending upward from the outlet of said lubricant-pump, a lubricant-supply tank, water-supplying means, valves and connections for supplying either lubricant from said tank or water from said water-supplying means to the lubricating system composed of said lubricant-pump and its supply and discharge pipes to displace either water or lubricant by the other as desired, said valves and connections including a lubricant-return pipe discharging into said supply tank for supplying the lubricant thereto when the lubricant in the lubricant system is displaced by water, and a pump driven from said shaft for moving the lubricant when desired from said supply tank to said lubricant system and vice versa as desired. 30
19. In a deep-well pump, the combination of a shaft extending down into the well, a rotary pump in the well, a water-discharge pipe extending up from said main pump, a lubricant-pump also located in the well, both of said pumps having rotors driven from said shaft, a lubricant-supply pipe leading to the intake of said lubricant-pump, a lubricant-discharge pipe extending upward from the outlet of said lubricant-pump, the upper ends of said lubricant-supply pipe and said lubricant-discharge pipe being interconnected to form a closed system, the lubricant system formed by said lubricant-pump and its supply and discharge pipes having a check-valved connection near the bottom to the interior of said water-discharge pipe permitting water inflow from said water-discharge pipe to said lubricant system, a lubricant-supply tank, water-supplying means, valves for supplying lubricant from said tank or said water-supplying means to said lubricant system at will so that either water or said lubricant may displace the other, and a pump for forcing lubricant to and from said supply tank. 40
20. In a deep-well pump, the combination of a shaft extending down into the well, a rotary pump in the well, a water-discharge pipe extending up from said main pump, a lubricant-pump also located in the well, both of said pumps having rotors driven from said shaft, a lubricant-supply pipe leading to the intake of said lubricant-pump, a lubricant-discharge pipe extending upward from the outlet of said lubricant-pump, the upper ends of said lubricant-supply pipe and said lubricant-discharge pipe being interconnected to form a closed system, the lubricant system formed by said lubricant-pump and its supply and discharge pipes having a check-valve connection near the bottom to the interior of said water-discharge pipe permitting water inflow from said water-discharge pipe to said lubricant system, a lubricant-supply tank, water-supplying means, and valves for supplying lubricant from said tank or said water-supplying means to said lubricant system at will so that either water or said lubricant may displace the other, said connections and valves including a line for discharging displaced lubricant back to said lubricant-supply tank, and a pump for forcing lubricant to and from said supply tank. 50
21. In a deep-well pump, the combination of a shaft extending down into the well, a rotary pump in the well, a water-discharge pipe extending up from said main pump, a lubricant-pump also located in the well, both of said pumps having rotors driven from said shaft, a lubricant-supply pipe leading to the intake of said lubricant-pump, a lubricant-discharge pipe extending upward from the outlet of said lubricant-pump, a lubricant-supply tank, water-supplying means, and valves and connections for supplying either lubricant from said tank or water from said water-supplying means to the lubricating system composed of said lubricant-pump and its supply and discharge pipes to displace either water or lubricant by the other as desired, and a pump for feeding lubricant from said supply-tank to said lubricant system. 60
22. In a deep-well pump, the combination of a shaft extending down into the well, a rotary pump in the well, a water-discharge pipe extending up from said main pump, a lubricant-pump also located in the well, both of said pumps having rotors driven from said shaft, a lubricant-supply pipe leading to the intake of said lubricant-pump, a lubricant-discharge pipe extending upward from the outlet of said lubricant-pump, a lubricant-supply tank, water-supplying means, valves and connections for supplying either lubricant from said tank or water from said water-supplying means to the lubricating system composed of said lubricant-pump and its supply and discharge pipes to dis- 70

place either water or lubricant by the other as desired, said valves and connections including a lubricant-return pipe discharging into said supply tank for supplying the lubricant thereto when the lubricant in the lubricant system is displaced by water, and a pump for moving the lubricant when desired

from said supply tank to said lubricant system and vice versa, as desired.

In witness whereof, I have hereunto set my hand at Indianapolis, Indiana, this 13th day of February, A. D. one thousand nine hundred and twenty three.

VICTOR SCHLEYER.
